CLOSURE MECHANISM FOR CONTAINERS

Theodore F. Schlicksupp, Long Island City, N. Y.

Application September 14, 1953, Serial No. 379,860

6 Claims. (Cl. 222—513)

This invention relates to closure and discharge or dispensing mechanisms for containers for paste-like material, such as toothpaste, toilet creams and the like, and for liquids, such as toilet water, skin lotions and the like. More specifically the invention relates to devices of this kind for closing collapsible or flexible containers, such as collapsible tubes which are closed at one end, plastic or flexible bottles, and also non-flexible bottles of glass and other materials.

The purpose of the invention is to provide a closure or dispensing mechanism which will produce a clean cut-off of the paste-like material after the desired amount has been discharged, and which will also produce a tight seal to prevent evaporation of the solvents or other vaporizable material which may be within the container.

Another object of the invention is to provide a discharge mechanism which can be manipulated with a minimum of effort and time.

A further object of the invention is to provide a discharge mechanism which, while not expensive to manufacture, is nevertheless durable and serviceable over a long period of time.

The invention will be described in connection with a discharge mechanism which is made in the form of an attachment device for application to the neck of a collapsible tube which is closed at one end, such for example as a toothpaste tube. The invention will be understood by a consideration of the accompanying drawings showing two modifications of such a discharge mechanism and from the detailed description thereof which follows.

In these drawings:

Fig. 1 is a view in elevation of a toothpaste tube with the device of the invention applied thereto;

Fig. 2 is a view of the discharge mechanism in vertical central section and drawn to an enlarged scale;

Fig. 3 is an exploded view drawn to the same scale showing the various parts of the mechanism separately, partly in elevation and partly in central section;

Fig. 4 is a transverse sectional view taken on line 4—4 of Fig. 2;

Fig. 5 is a detail plan view of one of the elements of the device; and

Fig. 6 is a view representing the development of a portion of the certain parts of the mechanism.

Describing the device briefly, and referring to Figs. 1-6 inclusive, the discharge mechanism of the invention comprises a body member 1 and a manually movable spout member 2. At the lower portion of body member 1 there is a collar 3 which is interiorly threaded to be screwed upon the threaded neck portion of a collapsible tube 4 for the purpose of mounting the device permanently upon the tube in place of the usual closure cap. The movable spout member 2 and a fixed central post member 5 are mounted within the upper part of body member 1.

Spout member 2 has an axial passageway 6 which is larger in diameter than post 5 so as to leave an annular passage to allow the flow of the paste-like material from the neck of the tube to the upper end of the spout. Such

2

upper end is contracted, preferably by a conical formation, as is shown, and provided with a discharge aperture 7. Adjacent this aperture there is an interior conical valve seat 8 which cooperates with a conical valve surface 9 on the upper end of post member 5, the post preferably projecting slightly beyond this conical surface to form a short cylindrical projection which fits closely in the discharge aperture 7, the end of the post being flush with the conical end of the spout member.

10 The spout member is turned or twisted by grasping a knurled flange 10 thereon, and a cam device, also to be described, causes the end of spout member 2 to move away from the end of post member 5 to the dotted position by a mere one-quarter turn of the spout, thereby fully opening the device to discharge the toothpaste or other material. The device is closed by a one-quarter turn in the reverse direction. Such a construction enables the mechanism to be fully opened or completely closed in an extremely quick and convenient movement. It also provides a tight closure to prevent evaporation.

Describing the mechanism in detail, the post member 5 at its inner end is fixed to or made integral with a perforated plate or disk 11, this disk having a series of perforations or holes 12 therein (Fig. 4) to allow the paste-like material to reach the annular passage between the post and spout member above referred to. The outer margin of plate 11 is clamped between the upper surface of collar 3 and a spacing ring or washer 13, which if desired may be made integral with plate 11.

30 Between the upper side of spacing collar 13 and a shoulder 14, which is formed on the interior of body member 1, is the rim portion of a spring member 15 and the margin of a sealing diaphragm 16, both of which will be presently described. These parts are all held in rigidly 35 fixed position by means of the internally threaded collar 3, and this collar is forced into the lower cylindrical skirt portion 17 of body member 1 with a force fit. The parts are preferably held together in this manner, although other means of securing the collar in position may be used, if desired.

Below the knurled flange 10 spout member 2 has a cylindrical portion 18, and formed on the surface of this cylinder there are two similarly shaped projections 19 and 19' arranged 180° from each other. Each of these 45 projections includes a helical, face cam surface 20 at the lower end of which is a locking lug 21. Cam surfaces 20 engage respectively two bosses 22 which project inwardly from opposite sides of a cylindrical bore 23 in the upper portion of body member 1. As the spout member 2 is turned by means of the knurled flange 10 these cam surfaces 20, engaging the lower edges of the bosses 22, force the spout member inwardly from the dotted position in Fig. 2 to the full line position where the discharge opening 7 is closed by the valve parts 8 and 9, previously referred to.

50 The relative position of bosses 22 and the cam surfaces 20 when the discharge aperture is closed is shown in Fig. 6. When the spout member is turned in the opposite direction one-quarter turn the cam surfaces slide along the lower corners of bosses 22 until the locking lugs 21 engage the left-hand edges of these bosses as indicated by the dotted position of bosses 22 in Fig. 6. Stop lugs 21 prevent the disengagement of the cam surfaces 20 from the lugs and the separation of the nozzle and body members.

65 In order to permit assembly of these parts, spaces 24 are arranged between the stop lugs 21 and the adjacent ends of the opposite cam formations 19 and 19'. These spaces are slightly wider than the width of bosses 22 so that in assembling the parts these bosses 22 are placed 70 opposite spaces 24 and the body member 2 moved inwardly and then turned slightly in order to move stops 21 beyond the bosses 22 and place the bosses in engage.

ment with the cams 20. Release of the spout member then allows the parts to be held in this position by means of the spring 15 previously referred to.

Spring 15 has an outer circular rim portion 25 by which it is clamped between the shoulder 14 on body member 1 and the upper surface of the spacing ring or washer 13. Projecting from the inner edge of rim portion 25 are three arcuate fingers 26 each terminating in a head portion 27 which projects radially from the end of its finger. The spring fingers 26 are normally, that is, they tend to remain, in the plane of the rim portion 25, and are displaceable therefrom during the rotation of the spout member 2 from open to closed position.

These head portions 27 engage the lower surface of a collar 28 which surrounds and makes a turning fit with the surface of a cylindrical projection 29 at the bottom of cylindrical portion 18 of the spout member, this projection being of reduced diameter. The width of collar 28 is preferably such that even when the spout member 2 is in its uppermost position spring fingers 26 are somewhat displaced from their normal plane so as to urge the collar upwardly.

The inner margin of sealing diaphragm 16 surrounds cylindrical projection 29 and is seated against a shoulder 30 at the upper end of this projection and held against this shoulder by the upper surface of collar 28 and the pressure of the three spring fingers 26. Collar 28, diaphragm 16 and shoulder 30 together form a seal between the lower end of the spout member 2 and the interior wall of body member 1 which permits both the rotatory and axial movements of the spout member. This seal prevents the escape of the contents of the container along the surface of bore 23 (Fig. 3), the spout member necessarily fitting rather loosely in this bore. It will be understood that when the spout member 2 is rotated from open to closed position and vice versa the cylindrical projection 29 turns in collar 28 which is held stationary by the spring fingers 26, and also that the surface of shoulder 30 turns with respect to the inner surface of the margin of diaphragm 16.

The spout member 2 is guided during its in and out movement by the outer surfaces of the two cam projections 19 and 19' which are cylindrical and which contact the surface of bore 23. It is also guided by the inner surfaces of bosses 22 contacting cylindrical portion 18. The lower end portion of the spout member is guided and maintained in its central position within this bore by means of the collar 28 and spring fingers 26. Consequently, the spout member moves coaxially with the post member 5 during the quarter turn opening and closing movements.

The closing device may be made of any suitable material, metal being preferred. Sealing diaphragm 16 is preferably non-resilient but highly flexible, polyethylene plastic being a suitable material.

It will be understood that the scope of the invention is set forth in the appended claims.

I claim:

1. In a discharge mechanism for containers, a body member constructed to be attached to the container, said body member having an axial bore at its outer end, a post-like member disposed within said bore and fixed at its inner end to said body member, a manually movable spout member mounted within said bore and projecting from said body member, said spout member surrounding said post and forming therewith an annular passage for the material to be discharged, cooperating valve and valve seat members on said respective post and spout members arranged to control a discharge aperture at the outer end of said spout member, cooperating cam formations on said spout and body members respectively to cause axial shifting of said spout member to an inner position to close said discharge aperture and to an outer position to open said discharge aperture when said spout member is manually rotated.

2. In a discharge mechanism for containers, a body member constructed to be attached to the container, a post-like member fixed at its inner end to said body member, a manually movable spout member projecting from a bore in said body member, said spout member surrounding said post and forming therewith an annular passage for the material to be discharged, cooperating valve and valve seat members on said respective post and spout members arranged to control a discharge aperture at the outer end of said spout member, spring means arranged to urge said spout member to open position, cooperating cam formations on said spout and body members respectively to effect axial shifting of said spout member to an inner position to close said discharge aperture and to an outer position to open said discharge aperture when said spout member is manually rotated, an annular diaphragm fixed at its outer periphery to said body member, a cylindrical extension of reduced diameter on said spout member forming a shoulder and projecting through the aperture in said diaphragm, a collar fitting said extension and permitting the turning movement of said spout member, said spring means being associated with said collar and causing the collar to clamp the inner periphery of said diaphragm against said shoulder to form a seal for preventing the escape of vaporized material from the interior of the container.

3. In a discharge mechanism for containers, a body member constructed to be attached to the container, a manually movable hollow spout member projecting from a bore in said body member, cooperating valve and valve seat members on said respective spout and body members arranged to control a discharge aperture at the outer end of said spout member, cooperating cam formations on said spout and body members respectively to cause axial shifting of said spout member to an inner position to close said discharge aperture and to an outer position to open said discharge aperture when said spout member is manually rotated, and spring means to maintain said cam formations in engagement with one another, said spring means comprising a rim portion fixed to said body member, and a plurality of arcuate fingers projecting from said rim portion and having their inner ends engaging said spout member at its inner end.

4. In a discharge mechanism for containers, a body member constructed to be attached to the container and having a cylindrical bore at its outer end, a manually movable spout member mounted within said bore and projecting axially from said body member, cooperating valve and valve seat members on said respective spout and body members arranged to control a discharge aperture at the outer end of said spout member, cam bosses projecting inwardly from said bore, cam formations on said spout member, said formations having cylindrical surface portions turning in said bore and face cam portions on their edges coacting with said bosses to cause axial shifting of said spout member to an inner position to close said discharge aperture and to an outer position to open said discharge aperture when said spout member is manually rotated.

5. In a discharge mechanism for containers, a body member constructed to be attached to the container, said body member having an axial bore at its outer end, a post-like member disposed within said bore and fixed at its inner end to said body member, a manually movable spout member mounted within said bore and projecting from said body member, said spout member surrounding said post and forming therewith an annular passage for the material to be discharged, cooperating valve and valve seat members on said respective post and spout members arranged to control a discharge aperture at the outer end of said spout member, cooperating cam formations on said spout and body members respectively to cause axial shifting of said spout member to an inner position to close said discharge aperture and to an outer position to open said discharge aperture when said spout member

is manually rotated, and spring means to maintain said cam formations in engagement with one another.

6. In a discharge mechanism for containers, a body member constructed to be attached to the container, a post-like member fixed at its inner end to said body member, a manually movable spout member projecting from a bore in said body member, said spout member surrounding said post and forming therewith an annular passage for the material to be discharged, cooperating valve and valve seat members on said respective post and spout members arranged to control a discharge aperture at the outer end of said spout member, spring means arranged to urge said spout member to open position, cooperating cam formations on said spout and body members respectively to effect axial shifting of said spout 10

15 member to an inner position to close said discharge aperture and to an outer position to open said discharge aperture when said spout member is manually rotated, an annular diaphragm fixed at its outer periphery to said body member, and means including said spring means for maintaining the inner margin of said diaphragm in sealing engagement with said spout member, so as to prevent the escape of vaporized material from the interior of the container.
